CLAIM

The ornamental design for a faceplate with a plug for charging a portable communications device, as shown and described.

DESCRIPTION

FIG. 1 is a front perspective view of a faceplate with a plug for charging a portable communications device;

FIG. 2 is a left side view thereof, the right side being a mirror image;

FIG. 3 is a top view thereof, the bottom view being a mirror image; and,

FIG. 4 is a front elevational view thereof.
